SURGICAL FORCEPS

Bruno Richter, Glen Ellyn, Ill.

Application August 24, 1948, Serial No. 45,871

4 Claims. (Cl. 128—321)

1

This invention relates to surgical forceps, and more particularly to ductus, coarctation and intestinal forceps, used to close tubular body vessels during surgery.

It is among the objects of the invention to provide improved surgical forceps which will firmly hold a tubular body vessel, such as a blood vessel, against pressure without penetrating or injuring the inner wall of the vessel, and which, pursuant to this object, is provided with closely-spaced, specially-shaped clamping teeth, the points of which are sufficiently close together to preclude penetration of a tubular body vessel to which the forceps are applied, but are sufficiently sharp and separated to obtain a firm grip on the outer wall of such a vessel.

Other objects and advantages will become apparent from a consideration of the following description and the appended claims in conjunction with the accompanying drawing, wherein:

Figure 1 is a plan view of a pair of surgical forceps illustrative of the invention;

Figure 2 is a side elevation of the forceps illustrated in Figure 1;

Figure 3 is a plan view on a greatly enlarged scale of a fragmentary end portion of the forceps illustrated in Figure 1, showing in detail the shape and arrangement of the clamping teeth of the forceps;

Figure 4 is a transverse cross-section of one of the jaw fragments illustrated in Figure 3, taken substantially on the line 4—4 of Figure 3; and

Figure 5 is a side elevation of a somewhat modified form of forceps or clip having the same type of teeth as particularly shown in Figures 3 and 4.

With continued reference to the drawing, the forceps comprise two similar side members 10 pivotally connected together intermediate their length in cross-over relationship by a pivotal connection including a pivot pin or screw 11 extending through registering apertures provided one in each of the side members 10. A pair of handle rings 12 is provided one ring on each side member 10 at one side of the pivotal connection, and a releasable lock 13 is provided between the side members adjacent the handle rings. This lock means may comprise a respective lug or extension projecting outwardly from each side member and provided on its face opposed to the face of the opposite lug with notches so that the two lugs are releasably engageable together to hold the forceps in closed condition. At the opposite side of the pivotal connection 11 from the handle rings 12 the side members con-

2

stitute jaw portions 14 of a reduced cross-sectional area, and a series of clamping teeth, as generally indicated at 15, is provided along the edge of each jaw member opposed to the opposite jaw member, and each series of teeth extends from the outer end of the corresponding jaw member longitudinally of the jaw member toward the pivotal connection 11. The construction is preferably such that the teeth near the outer ends of the jaw members overlap or interengage when the forceps are tightly closed without any tissue or other material included between the opposed series of teeth.

The above-described construction of surgical forceps is conventional, and the present invention resides primarily in so shaping and spacing the clamping teeth that the teeth will firmly grip the outer wall of a tubular body vessel, such as a blood vessel, so that the forceps will hold the vessel closed against blood pressure, even if the vessel be severed near the forceps, but the teeth will not penetrate or injure the inner wall portion of the vessel to thus delay healing of the vessel or cause other undesirable effects.

25 The individual teeth of the series 15 are particularly illustrated in Figures 3 and 4, and indicated at 16. While the size and shape of the teeth may vary within very restricted limits, highly satisfactory results have been accomplished with 30 clamping teeth approximately 0.045 of an inch in height from the bases to the pointed outer ends thereof, and with the pointed outer ends of adjacent teeth in a series spaced apart a distance of approximately 0.025 of an inch.

35 The opposite side walls of each tooth extending transversely of the corresponding jaw converge from the base of the tooth to a point at the outer end of the tooth at a total included angle in the range between 10° and 15°, and the opposite 40 sides of each tooth extending longitudinally of the corresponding jaw converge from the base of the tooth to a point at the outer end of the tooth at a total included angle of approximately 35°. This provides an arrangement in which the 45 teeth are approximately 0.045 of an inch high and approximately 40 teeth are disposed in an inch of jaw length. The sides of the jaws are dressed or finished to a smooth, rounded shape, resembling in cross-section a streamlined body, and 50 the opposite sides of each tooth extending longitudinally of the corresponding jaw are somewhat convexly curved, as is clearly illustrated in Figure 4.

The jaws are arranged so that the pointed outer ends of the teeth projecting from one

jaw are disposed substantially midway between the pointed outer ends of corresponding teeth projecting from the other jaw when the jaws are closed together, as illustrated in Figure 3, with the teeth near the outer ends of the jaws intermeshing and the teeth at the inner ends of the series of teeth being somewhat spaced apart at their outer ends, the angle between two lines one of which contacts the outer ends of the teeth of one series and the other of which contacts the outer ends of the teeth of the other series when the jaws are closed together including between them a total angle of approximately 10°. In the somewhat modified device shown in Figure 5, the handle rings 12 and locking tongues 13 are not used and the side members 16 are not crossed over, but are pivotally connected together in side-by-side relationship by a pivot pin 17 extending through overlapping apertured lugs 18 extending laterally from the two side members.

At the side of the pivot pin 17 opposite the teeth 15, the two side members are shaped to provide angularly-disposed levers 19 relatively diverging in a direction away from the pivot pin to separate the teeth-carrying jaws 20 when the levers are compressed, and a coiled compression spring 21 is disposed between the levers to resiliently urge the levers apart and the jaws together. This spring is held in position by spring seats 22 secured one to the inner side of each lever 19 and operatively engaging the corresponding end of the spring 21.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

I claim:

1. In a pair of surgical forceps comprising a pair of side members, a pivotal connection interconnecting said side members intermediate their length in crossed-over relationship, respective handle rings on said side members at one side of said pivotal connection, respective jaw portions on said side members at the opposite side of said pivotal connection, and a series of teeth on the inner side of each jaw member extending longitudinally and transversely of each jaw member from the outer end of the latter toward said pivotal connection and so arranged that the teeth of one series are received between the teeth of the opposite series when the jaws are closed, the improvement wherein the sides of each tooth extending transversely of the corresponding jaw member converge relative to each other from the jaw to a point at the outer end of the tooth at a total included angle in the range between 10° and 15°, and the side walls of each tooth disposed longitudinally of the corresponding jaw member converge from the jaw member to the pointed outer end of the tooth at an angle of approximately 35°, and adjacent transverse side walls converge at the bases of said teeth.

2. In a pair of surgical forceps comprising a pair of side members, a pivotal connection interconnecting said side members intermediate their

length in crossed-over relationship, respective handle rings on said side members at one side of said pivotal connection, respective jaws on said side members at the opposite side of said pivotal connection, and a series of teeth on the inner side of each jaw extending longitudinally and transversely of each jaw from the outer end of the latter toward said pivotal connection and so arranged that the teeth of one series are received between the teeth of the opposite series when the jaws are closed, the improvement wherein said teeth are approximately 0.045 of an inch in height and pointed at their outer ends with the pointed outer ends of adjacent teeth in a series spaced apart approximately 0.025 of an inch.

3. In a pair of surgical forceps comprising a pair of side members, a pivotal connection interconnecting said side members intermediate their length in crossed-over relationship, respective handle rings on said side members at one side of said pivotal connection, respective jaws on said side members at the opposite side of said pivotal connection, and a series of teeth on the inner side of each jaw extending longitudinally and transversely of such jaw from the outer end of the latter toward said pivotal connection and so arranged that the teeth of one series are received between the teeth of the opposite series when the jaws are closed, the improvement wherein said teeth are approximately 0.045 of an inch in height and are disposed in said series at approximately 40 teeth to an inch of jaw length.

4. In a pair of surgical forceps comprising a pair of side members, a pivotal connection interconnecting said side members intermediate their length in crossed-over relationship, respective handle rings on said side members at one side of said pivotal connection, respective jaw portions on said side members at the opposite side of said pivotal connection, and a series of teeth on the inner side of each jaw member extending longitudinally and transversely of each jaw member from the outer end of the latter toward said pivotal connection and so arranged that the teeth of one series are received between the teeth of the opposite series when the jaws are closed, the improvement wherein the sides of each tooth extending transversely of the corresponding jaw member converge relative to each other from the jaw to a point at the outer end of the tooth at a total included angle in the range between 10° and 15°, and the side walls of each tooth disposed longitudinally of the corresponding jaw member converge from the jaw member to the pointed outer end of the tooth at an angle of approximately 35°, and adjacent transverse side walls converge at the bases of said teeth, said tooth walls extending longitudinally of the corresponding jaw being convexly curved.
